CLAIM

The ornamental design for a modular desk, as shown and described.

DESCRIPTION

FIG. 1 is a perspective view of a modular desk showing my new design;

FIG. 2 is a top plan view of the modular desk of FIG. 1; FIG. 3 is a bottom plan view of the modular desk of FIG. 1; FIG. 4 is front elevation of the modular desk of FIG. 1, with the back side elevation being the same;

FIG. 5 is a right side elevation of the modular desk of FIG. 1, with the left side elevation being the same;

FIG. 6 is an exploded view of FIG. 1;

FIG. 7 is a perspective view of the desktop of the modular desk of FIG. 1, shown separately for ease of illustration;

FIG. 8 is a top plan view of the desktop of FIG. 7;

FIG. 9 is a bottom plan view of the desktop of FIG. 7; FIG. 10 is front elevation of the desktop of FIG. 7, with the back elevation being the same; and,

FIG. 11 is a right side elevation of the desktop of FIG. 7, with the left side elevation being the same.

The dashed lines shown in the drawing Figures are meant to illustrate environment and form no part of the claimed design. The dot-dashed lines shown in the drawing Figures are meant to indicate alignment in the exploded views, and form no part of the claimed design.

The modular desk is shown with symbolic breaks in its length and height. The appearance of any portion of the article between the break lines forms no part of the claimed design.
